DESIGN FOR A SHARPENER

Avery W. Walker, Niagara Falls, N. Y., assignor
to The Carborundum Company, Niagara Falls,
N. Y., a corporation of Delaware

Application November 16, 1937, Serial No. 72,939

Term of patent 7 years

To all whom it may concern:

Be it known that I, Avery W. Walker, a citizen of the United States of America, residing in Niagara Falls, county of Niagara, State of New York, have invented a new, original, and ornamental Design for a Sharpener, of which the following is a specification, reference being had to the accompanying drawing forming a part thereof.

Figure 1 is a perspective view of a sharpener showing my new design in open position;

Figure 1a is a plan view of the cover on a reduced scale;

Figure 2 is a side elevational view of the sharpener in closed position; and

Figure 3 is an end view thereof.

I claim:

The ornamental design for a sharpener, substantially as shown and described.

AVERY W. WALKER.
